UNITED STATES PATENT OFFICE.

JOHN P. TARBOX, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

LATCH MECHANISM.

Application filed November 14, 1925. Serial No. 68,958.

The principal object of my invention is the embodiment in a latch mechanism adapted to circumvent the window pane of an automobile door, of an interlocking device adapted to make connection between the inside and outside latch operating devices without making apertures or recesses in the jamb rail of the door, as is necessary in a number of such devices which have been proposed. In all of said applications, so far as I am aware, it is necessary to aperture or recess the jamb rail of the door in order to accommodate the interlocking device. Such aperturing or recessing, as the case may be, somewhat weakens the jamb rail of the door and in any case where the aperture or recess is visible from the exterior it detracts to a degree from the finished appearance of a high grade product. This is quite as true when the interlocking device is mounted on the door post as when it is mounted on the jamb rail.

My invention will be the more fully understood and its advantages more certainly appreciated from a comprehension of the embodiment which I show in the accompanying drawings.

In the drawings, Figure 1 is a substantially central horizontal section of an automobile door structure embodying my invention;

Fig. 2 is a three quarters front perspective view of that section of the door post opposite the latch mechanism;

Fig. 3 is a three quarters front view of the inside latch operating mechanism; and

Fig. 4 is a corresponding view of the outside latch operating mechanism in connection with the associated part of the jamb rail of the door.

According to my invention I constitute the glass run channel by means of which the window pane of the door is slidably mounted on the jamb rail, the interlocking member of the latch mechanism. This I accomplish by mounting the glass run channel in suitable guides whereby it may be vertically reciprocated along the inner face of the jamb rail of the door. This done, I connect the inside and outside latch operating mechanisms to the vertically reciprocable glass run channel in such manner that they partake of its movements in a fashion to operate the latch bolt in relation with its

keeper to effect engagement and disengagement of the latch.

The jamb rail of the door is designated by the numeral 10. It is formed of pressed metal and is of an angular cross section embodying in its mid portion a rabbet 11 and at its inner and outer edges, respectively, an inner flange 12 and an outer flange 13. The outer flange serves for the connection of the outer panel 14 and with the connected outer panel 14 constitutes the outer over-lap of the door upon the crack of the jamb. The inside flange 12 serves for the connection of the locking board 15 and for further purposes not necessary to discuss here.

Within the body of the door is mounted the glass 16 which constitutes the extensible member of the door and is adapted to be raised and lowered to close and open the window of the door. On the jamb rail it is mounted in a glass run channel 17 which lies over against the inner face of the jamb rail 10. A similar mounting is provided on the opposite or hinge rail of the door, but this is not shown here since it does not enter directly into this invention. Suffice it to say that by reason of such mountings the extensible member 16 is substantially of the full width of the door, and has its side edge 18 moving in close proximity to the jamb face of the door itself.

The inside latch operating device 19 embodies as its principal element the horizontal sliding latch bolt 20. This is confined to its reciprocatory path by means of stamped metal guides 21 secured to a base plate 22. The base plate 22 in turn is secured either to the lock board 15 or to the inner face of the jamb rail 10, or to both as may be preferred. A vertically extending lever 23 pivoted at 24 to the base plate 22 below the bolt 20 is provided for operating this bolt from the inside of the body. This lever 23 passes through a vertical slot 25 on the inside of latch bolt 20. But engagement with the latch bolt is not direct. Such engagement is made through the bell crank 26 one arm of which 27 engages the bolt at the inner end of the slot 25 and the other arm of which 28 extends toward the jamb rail and is provided with a pin 29 for a purpose presently to appear. The lever 23 engages the rear edge of the arm 27 and by bearing upon it operates the latch bolt 20. The

latch bolt itself, the lever 23 and the arm 27 are together held in projected position by a spring 30 housed within an aperture 31 in the interior of the bolt 20 and bearing 5 at its outer end 32 against the bolt and at its inner end against a tang 34 struck inwardly of the slot 25 and the aperture 31 from the base plate 22.

The outside latch operating mechanism 10 35 is comprised of the outside operating handle 36, the rotatable spindle 37 with which it is connected, the base plate 38 mounted on the spindle and in turn mounted upon the jamb rail of the door, and the 15 oscillatable arm 39 connected with the spindle. The base plate 38 has its opposite ends flanged as at 40 and 41, respectively, the flanged end 40 is reversely bent to provide a duplex bearing for the spindle. The 20 flange 41 bears directly against the inner face of the jamb rail. A biasing spring 42 of light pressure, as compared with the spring 30, is so arranged as to bias the arm 39 normally upward.

25 Arm 39 of the outside latch mechanism is interlocked with the arm 28 of the inside latch mechanism through the intermediary of the glass run channel 17. This glass run channel is mounted for vertical reciprocation in guides 43 and 44 secured to the inner face of the jamb rail 10 and confining the glass run channel for vertical sliding movement thereagainst in the angle between the main body of the rail and the rabbeted portion 35 11. The outside of the glass run channel has mounted a pin 45 having a pin and slot connection with the arm 39 of the outside latch operating device, while the inside wall of the glass run channel 18 is provided 40 with an inwardly extending arm 46 making a pin and slot connection with the pin 29 carried by the bell crank arm 28 to bell crank 26.

45 On the door post 47, which is likewise of stamped metal and in this case of channel section, is fixedly mounted a keeper 48 in position to coact with the latching end 49 of the bolt 20.

50 It being desired to open the door from the inside one has only to move the lever 23, which, through its bearing on the arm 27 of bell crank 26, actuates the bolt directly to reciprocate it against the pressure of spring 30 from its latch engagement with the keeper 48. This movement through the bell crank 28 also moves the glass run channel 17 in the vertical plane and through it moves the outside operating handle 36, but the parts are light and the movement simple, 55 60 while the bearing surfaces are very large so that there is no undue friction or wear of the parts. Desiring to open the door from the outside one but grasps the handle 36 and rotates it counter clock-wise a portion of a turn whereupon the glass run chan-

nel 17 is moved vertically and through such engagement moves the arm 28 and bell crank 26 counter clock-wise to effect withdrawal of bolt 20 through engagement of slot 27, but in this case the inner arm 23 is not 70 operated. Operated from the outside the inside and outside latch operating devices are independent. To close the door one has but to push it closed and the bolt 20 will ratchet over the coacting faces of the keeper 75 48. Or else one may operate either the inside or the outside latch operating devices to withdraw the bolt 20, then push the door closed and afterward release the operating devices to allow the bolt to slide into place 80 behind the keeper.

It will be observed that except for the projection of the sliding bolt 49 through the web of the jamb rail, the jamb rail has not been pierced in any way nor has its exterior been given any irregularity of form. It is strong. It is neat. In accomplishing this, use has been made of an element, the glass run channel, already and certainly present in many structures. To constitute 90 it an interlocking device it has been but necessary to provide it with suitable guides. Any number of these in any suitable location may be provided. They may, moreover, be of any suitable form. The glass run channel 95 is light, yet stiff by reason of its channel form, and mounted in the angle of the rabbet its bearing surfaces are extensive and greatly elongated whereby it transmits its interlocking movements without bias and 100 without undue friction; yet further, by very reason of the use of this channel to serve this function, the side edge of the glass is retained in the very closest proximity to the inner face of the jamb rail, it being unnecessary to interpose between it and this face 105 any other member.

The modifications of my invention without departing from its generic nature may be but few but these few I deem should unfailingly fall within the scope of the attached claims.

What I claim is:

1. In combination with an automobile door of the type adapted to have an extensible member of substantially the full width of the door arranged for slidable movement therein with its side edge in close proximity to the jamb face of the door, inside and outside latch operating devices on opposite sides of the projected path of movement of said extensible member, and an interlocking device extending around the side edge of said extensible portion and partaking of a movement in the vertical plane in its interlocking function.

2. In combination with an automobile door of the type adapted to have an extensible member of substantially the full width of the door slidable therein with its side edge

- in close proximity to the jamb face of the door, inside and outside latch operating devices on opposite sides of the projected path of movement of said extensible member, and
- 5 an interlocking device extending around the side edge of said extensible portion and partaking of a vertical sliding movement in its interlocking function.
3. In combination with an automobile door of the type adapted to have an extensible member of substantially the full width of the door slidable therein with its side edge in close proximity to the jamb face of the door, a vertically reciprocable run channel for the extensible member, and inside and outside latch operating devices on opposite sides of the projected path of movement of said extensible member, said run channel constituting an interlocking device between the outside and inside operating device.
- 10 4. In combination with an automobile door of the type adapted to have an extensible member of substantially the full width of the door slidable therein with its side edge in close proximity to the jamb face of the door, inside and outside latch operating devices on opposite sides of the projected path of movement of said extensible member, and an interlocking device extending around the side edge of said extensible portion and partaking of a movement in the vertical plane in its interlocking function, said interlocking device comprising a member of thin flat form in the region where it traverses the projected path of movement of the extensible portion, whereby it is interposed between the side edge of the extensible portion and the jamb face of the door without substantial removal of the extensible portion from the jamb face.
- 15 5. In combination with an automobile door of the type adapted to have an extensible member of substantially the full width of the door slidable therein with its side edge in close proximity to the jamb face of

the door, inside and outside latch operating devices on opposite sides of the projected path of movement of said extensible member, and an interlocking device extending around the side edge of said extensible portion and partaking of a movement in the vertical plane in its interlocking function, said interlocking device comprising a member sliding vertically between the side edge of the extensible portion and the jamb face of the door and effecting the interlocking connection with the latch operating devices through pin and slot connections.

20 6. In combination with an automobile door of the type adapted to have an extensible member of substantially the full width of the door slidable therein with its side edge in close proximity to the jamb face of the door inside and outside latch operating devices on opposite sides of the projected path of movement of the extensible member, and an interlocking device extending around the side edge of said extensible portion and partaking of a movement in the vertical plane in its interlocking function, said interlocking device comprising a relatively thin flat member interposed between the edge of the extensible member and the inner plane of the jamb rail of the door.

25 7. In combination with an automobile door of the type adapted to have an extensible member of substantially the full width of the door slidable therein, a vertically reciprocable run channel for the extensible member, and a latch mechanism, said latch mechanism comprising inside and outside latch operating devices arranged on opposite sides of the projected path of movement of said extensible member and operatively connected with said run channel, whereby when either of said latch operating devices is actuated the run channel is reciprocated.

In testimony whereof I hereunto affix my signature.

JOHN P. TARBOX.
